UNITED STATES PATENT OFFICE.

LUD. HOLLAND-LETZ, OF OAK PARK, ILLINOIS, ASSIGNOR TO INTERNATIONAL HARVESTER COMPANY, A CORPORATION OF NEW JERSEY.

FIBER-HANDLING MECHANISM.

1,415,930.

Specification of Letters Patent. Patented May 16, 1922.

Application filed July 17, 1919. Serial No. 311,522.

To all whom it may concern:

Be it known that I, LUD. HOLLAND-LETZ, a citizen of the United States, residing at Oak Park, in the county of Cook and State of Illinois, have invented certain new and useful Improvements in Fiber-Handling Mechanism, of which the following is a full, clear, and exact specification.

This invention relates to mechanism for handling fiber, such as hemp, flax, sisal, etc., and more particularly, to means for guiding the fiber in its passage from one machine to another and for depositing said material in position to be fed to the second machine in a direction transverse to its length.

The particular problem which led to the present invention is that of handling hemp and of properly positioning hemp for its feeding movement through a scutcher after the hemp has passed through the hemp brake. The most common type of hemp brake is the roller brake which comprises a plurality of pairs of corrugated rollers between which the hemp stalks are fed longitudinally. Hemp scutchers are used to clean the hemp after it has been passed through the brake and to comb out the woody material or hurds from the hemp fiber.

In one form of scutcher the broken hemp is gripped intermediate its ends, and the ends of the fiber are combed out, thereby removing the hurds.

From this brief outline of the braking and scutching operations, it will be seen that the hemp is fed longitudinally through the roller brake, but is fed through the scutcher in a direction transverse to its length, or substantially at right angles to its direction of movement through the brake.

In view of this change in the direction of feeding movement, it is necessary either by manual or mechanical means to receive the hemp as it comes from the brake and to guide and position, or deposit the hemp in such a manner that it may be gripped intermediate its ends and be fed through the scutcher.

The invention has for its object, therefore, to receive, guide and position or deposit fiber, such as broken hemp, in such a manner that the direction of feeding movement of this material may be changed.

A further object is to provide means for receiving, guiding and positioning fiber in such a manner that the fiber is so deposited

that it may be fed in a direction transverse to its length or transverse to its former direction of feeding movement.

Another object is to clamp and hold the fiber in a position against the fixed member as the remaining part of the fiber is being guided and positioned upon said fixed member for feeding movement.

A still further object is to hold the fiber at one point in its length as the remaining portion of the fiber is so guided and positioned that it may be fed in a direction transverse to its length, but to hold the fiber in such a manner that this holding means is rendered ineffective or inoperative before the guiding and positioning means has completed its function or operative movement.

A still further object is to provide means for varying the point of release of the clamping or holding means with respect to the cycle of movement of the guiding and positioning means.

With these objects in view and with further objects which will appear as the description proceeds, the invention consists briefly of mechanism which is interposed between the hemp brake and the hemp scutcher and receives the broken hemp from the brake or from a conveyor leading from the brake, and guides and positions the broken hemp in such a manner that it may be fed through the scutcher in a direction transverse to its length. In this instance the mechanism in which the invention is embodied is mounted upon a fixed support arranged longitudinally with respect to the axis of the scutcher and adjacent and slightly below the delivery end of a conveyor which receives the hemp from the brake. As the hemp passes over the delivery end of the conveyor it will fall by gravity adjacent one side of the fixed support, and means is provided for clamping the hemp against one side of the fixed support and for guiding the remainder or free end portion of the hemp over the top of the support and to a position in which the said end portion rests against the opposite side of the fixed support. A feeding member passes along the upper surface of the fixed support, and as this member is preferably in continuous operation, means is provided for releasing the clamping or holding means which retains the hemp in position against

the support before the hemp guiding and positioning means has completed its movement in a direction to position the free ends of the hemp.

5 In the embodiment of the invention illustrated, means has also been provided for normally clamping the hemp against the delivery end of the conveyor which receives the hemp from the hemp brake, and this 10 clamping means is so connected to the guiding and positioning means that as the hemp is received and acted upon by the guiding and positioning means, the means for holding the hemp in engagement with the delivery end of the conveyor is automatically released.

One embodiment of the invention has been 20 illustrated in the accompanying drawings, and in these drawings

25 Fig. 1 is a front elevation showing my improved mechanism mounted on a fixed support adjacent a hemp scutcher, and also showing the delivery end of the conveyor which receives the hemp from the brake;

25 Fig. 2 is a side elevation of construction shown in Fig. 1;

30 Fig. 3 is a front elevation on an enlarged scale, showing my improved hemp handling mechanism, the mechanism in this view being shown in the position assumed just prior to the release of the clamping means, the positioning and guiding means being shown in its intermediate position of movement;

35 Fig. 4 is a front elevational view similar to Fig. 3, but showing my improved mechanism in its inoperative position, or position of rest;

40 Fig. 5 is a front elevational view similar to Figs. 3 and 4 but showing the mechanism in the position assumed when it has completed its operative movement;

45 Fig. 6 is a detail elevational view on an enlarged scale of the main casting used in my improved mechanism;

45 Fig. 7 is a top plan view of construction shown in Fig. 6;

50 Figs. 8 and 9 show in plan and side elevation a pivoted member which controls the movement of the clamping and holding means; and

55 Fig. 10 is a detail plan view, partly in section, illustrating the adjustable means for varying the period of action of the clamping or holding means.

55 Referring to Figs. 1 to 3, the delivery end of the conveyor which receives the hemp from the brake is illustrated at 20, means in the form of a roller 21 being provided for normally holding the hemp in contact with 60 the conveyor. Roller 21 is carried by arms 22 pivoted at 23 to the conveyor casing, and this roller is normally held in engagement with the conveyor by gravity. As illustrated in Fig. 1, one of the arms 22 is extended beyond the pivot 23, as shown at 24,

and shock absorbing or cushioning means is provided and co-operates with the arm 22, this means comprising a rod 25 which passes through a suitable aperture 26 in the arm 24, and is provided with a nut or head 70 27 which normally rests against the arm 24. The rod 25 is passed through a lug 28 carried by the casing of the conveyor and is encircled by a coil spring 29 which is interposed between a nut 30 and the lug 28. A 75 fixed supporting member 31 is mounted on framework 32 adjacent the hemp scutcher 33 and an endless conveyor 34 is suitably supported on sprocket wheels 35 and 36 carried by the supporting member and feeds 80 the hemp into the scutcher 33. The hemp which has passed between the pairs of rollers of the roller brake is fed by the rollers on to the end of the conveyor 20, and travels on said conveyor to the delivery end thereof. 85

The object of the present invention, as stated above, is to receive the material as it comes from the roller brake and the conveyor, and to position it in such a manner that it may be gripped and fed in a direction 90 transverse to its length through the scutching mechanism.

Referring to the present structure, therefore, the problem to be solved is to receive the hemp from the delivery end of the conveyor 20 and to position the hemp on the supporting member 31 in such a manner that the chain 34 will engage the hemp intermediate its ends and preferably at a medial point, and will feed the hemp in a direction 100 transverse to its length.

As above pointed out, the improved hemp handling means is made up of two parts, namely, the means for clamping or holding the hemp against the supporting member 31, 105 and the means for guiding and positioning the hemp on said supporting member as it is being held.

In the embodiment of the invention illustrated, the guiding and positioning mechanism is positively actuated, and this mechanism engages, during a portion of its movement, the clamping and holding means, thereby rendering this clamping means operative during a portion of the movement of 115 the guiding and positioning mechanism. This last-named mechanism is pivotally supported on a casting 37 rigidly secured by bolts 38 to the supporting member 31, and provided with the outwardly extending pivot 120 pin 39. The clamping and positioning means is carried by a main casting 40 pivoted on the pivot pin 39, but secured against removal by a cotter pin 41. An arm 42 is bolted to the casting 40 as shown at 43, and is provided with a laterally extending handle 44 by means of which this arm is manually operated. A rod 45 is rigidly clamped to the arm 42 and extends in a direction toward the scutcher mechanism, or 130

along the longitudinal axis of the supporting member 31. A second arm 46 is also rigidly secured to the casting 40 by bolts 47, the arms 42 and 46 being disposed at substantially a right angle to each other. A shield or guiding member 48, arcuate in cross section, is secured to the rod 45 and to a rod 49, carried by the arm 46 adjacent its outer extremity. From the showing in Figs. 1, 2 and 10 4, it will be seen that this shield 48 forms with the adjacent surface of supporting member 31 a pocket or receptacle for receiving and guiding the hemp as it falls from the delivery end of the conveyor 20. An angle 15 iron frame member 50 is rigidly bolted to the supporting member 31 below the guiding and positioning means, and is provided at one end with an outwardly extending portion 51, to which are connected the ends of 20 counterbalancing springs, hereinafter described, and at its opposite end the member 50 is provided with an outwardly and upwardly extending portion 52 which forms a rest for the arm 42 when said arm is disposed in its normal or inoperative position. 25 The casting 40 is also provided with an offset lug 53 which in turn is slotted as shown at 54. A member 55 is adjustably secured to the lug 53 by means of a bolt 56 which passes through the slot 54 and a counterbalancing or cushioning spring 57 is secured at one end to the member 55, and at its opposite end by means of a screw-threaded adjustment shown at 58 to the offset end portion 51 of the 30 frame member 50. From the illustration of Figs. 4 and 5 it will be seen that the spring 57 assists the operator in swinging the guiding and positioning means about its pivot through the initial movement thereof, and 35 also as shown in Fig. 5, the spring acts as a counterbalance or cushioning spring when the positioning and guiding means has reached its limit of operative movement. By adjusting the member 55 with respect to 40 the lug 53, the effectiveness of this spring and the point at which the force of the spring takes effect may be varied.

As above stated, in the present embodiment of the invention, the means for clamping and holding the hemp against the supporting member 31 is actuated by means of the guiding and positioning member, and next in order I will describe the portions or parts of the guiding and positioning mechanisms which perform this function.

The casting 40 is extended below the pin 39 upon which this casting is pivoted, this lower portion being substantially triangular in outline, as shown at 59. The extreme 60 lower edge of this lower portion of the casting is provided with a laterally extending flange 60 which extends from a point 61 on the casting to a point 62, the latter point being located at a distance from one edge of 65 the casting. The flange 60 forms a cam sur-

face which engages a roller 63 carried by an arm 64 journaled on a pivot pin 65, this pin being carried by a casting 66 which is bolted, as shown at 67, to the supporting member 31 in a position below the casting 37. In order 70 to provide for a variable point of release for the roller 63 from the cam or flange 60, an extension of this flange is adjustably carried by the casting 40, this extended portion 68 overlapping a portion of the flange 60, as 75 illustrated in Fig. 10. The portion 68 is provided with a downwardly extending lug 69 having a serrated lateral edge, as shown at 70, which engages a serrated edge 71 formed on the casting 40. The lug 69 is secured to 80 the casting 40 by means of a bolt 70' which passes through an arcuated slot 72 formed adjacent the lower end of the casting 40. If the operator therefore desires the holding or clamping means to remain operative for 85 a longer time, the extension 68 of the flange 60 is adjusted in a direction toward the adjacent edge of the casting 40, or in a clockwise direction (see Fig. 1), and if the operator desires the holding or clamping means to 90 be released earlier this extension 68 is adjusted in the opposite direction.

The arm 64 above described is a main actuating member for the clamping and holding means, and the structure of this holding 95 or clamping means and the connections between the arm 64 and this means will next be described.

In addition to the arm 64, a casting 73 is pivotally mounted on the pin 65, this 100 casting having secured thereto an arm 74 which carries at its outer end a rod 75, the rod extending laterally from the arm in a direction toward the scutching machine, or parallel to the longitudinal axis of the supporting member 31. The casting 73 also has secured thereto at an angle to the arm 74 an arm 76 which is connected at its outer end to a rod 77, this rod being bent upwardly at an angle as shown 110 at 78, and being slidably connected at its upper end with a laterally extending lug 80 which is carried by the outer extremity of the arm 22 and adjacent the roller 21. Stops 81 and 82 are carried by the rod 77 115 and limit the movement of the rod in the lug 80, a buffer spring 83 being carried by the rod adjacent the lower stop 82. From this description it will be seen that as the arm 76 is moved about its pivot in an anti-clockwise direction (see Fig. 3) the rod 77 will be moved vertically and will lift the arm 22 and with it the roller 21. These elements are so connected together that the roller 21 will be lifted approximately at the period 125 in the movement of the handling mechanism when the rod 75 holds the hemp against the side surface of the supporting member 31. This position in the operation of this mechanism is illustrated in Fig. 3. Since the cam 130

or flange 60 carried by the casting 40 must necessarily engage and release the roller 63 intermittently, it is necessary that this roller engaging portion of the casting 40 be so constructed that it will engage the roller during its movement in one direction, but will yield during its movement in an opposite direction in such a manner that neither the roller nor the engaging surface will be injured. Provision has been made for fulfilling this condition, and the means for accomplishing this result comprises a cam member 84 which is pivoted at 85 to the casting 40.

As illustrated in Figs. 8 and 9, the member 84 is laterally offset, as shown at 86, this offset portion being normally disposed in a position adjacent the edge 61 of the flange 60, thus forming an extension of said flange. A portion 87 of the pivoted member 84 disposed on the opposite side of the pivot of said member from portion 86 is located adjacent the outer surface of the casting 40, and is provided at its rear end with an apertured lug portion 88. The casting 40 has preferably formed integral therewith an offset lug 89 so located with respect to the pivot of the member 84 that the lug 88 carried by the pivoted member will be disposed directly beneath this lug 89. A rod 90, having on one end a head 91 is passed through the apertured lug 88 and through the offset lug 89, and carries a coil spring 93 which engages at one end a cotter pin 92 which passes through the rod 90, and at its opposite end the upper surface of the lug 89. From this description it will be obvious that the spring 93 normally retains the pivoted member 84 in the position shown in the drawing, and that the pivoted member 84 may yield upon the return movement of the guiding and positioning mechanism in order to permit this mechanism to assume its normal position shown in Fig. 4, and to pass over the roller 63 which will engage the under surface of the pivoted member 84 during the return movement of the latter.

The clamping and holding means is operatively connected to the arm 64 by means of a spring 94 which is secured at one end, as shown at 95, to the free end of the arm 64 and at its opposite end is adjustably secured to the lateral offset end 96 of an arm 97, this latter arm being rigidly secured by suitable means, such as bolts 98, to the arm 74 and 76, which carry the clamping and holding rod 75. The tension on the spring 94 is so adjusted by means of the screw-threaded connection 99 between this spring and the offset end 96 of the arm 97 that this spring normally acts as a rigid connection between the actuated arm 64 and the arms 74 and 76. However, when the rod 75 has been adjusted to a position in engagement with the side surface of the supporting member 31, the spring 94 is expanded as shown in Fig. 3,

and provides a resilient connection maintaining the rod 75 in engagement with the supporting member 31 until the roller 63 is released from the cam action of the extension 68 of the flange 60 carried by the casting 40. A counterbalancing spring 100 is also provided for the arm 64, being connected at one end to a lug 101 carried by the arm 64, and being adjustably connected at its opposite end as shown at 102 to the portion 51 of the frame member 50. Means has been provided for supporting the arm 74 in its inoperative position, or position of rest, this means comprising a laterally extending stud 103 suitably supported on the upwardly extending and offset portion 52 of the frame member 50, and on a substantially parallel upwardly extending portion of the frame member 50.

Having described the construction of my improved holding and clamping means and of the mechanism for guiding and positioning the hemp, I will now define the operation of these constructions.

The normal position, or position of rest of these structures is illustrated in Figs. 1 and 4, and in this position arm 42 rests against the stop formed by the upper end of the portion 52 of the frame member 50 and the arm 74 rests against the stop formed by the stud 103 also supported by the frame member 50. After one feeding of hemp has been passed through the hemp brake this hemp will travel upwardly on the delivery conveyor over the delivery end 20 of this conveyor. As the hemp falls by gravity from the delivery end 20 of the conveyor and reaches a position in which substantially half of the hemp is disposed below the upper surface of the supporting member 31, the operator grasps the handle 44 and swings the arm 42 and the guiding and positioning means carried thereby in an anti-clockwise direction. As this guiding and positioning means is swung in this direction, the pivoted member 84 carried by the casting 40 will engage the under surface of the roller 63 and will swing the arm 64 about its pivot 65 and through the spring connection 94, and arm 97 will also swing the arm 74 and the clamping and holding rod 75 in an anti-clockwise direction. When the rod 75 has been swung to a position in engagement with the side surface of the supporting member 31, as shown in Fig. 3, the spring 94 is expanded, thereby resiliently holding this rod in engagement with the supporting member. As one portion of the hemp is being held in engagement with the supporting member by the rod 75, the free ends of the hemp will be engaged by the rod 45 and guiding shield 48, and will be carried over the top surface of the supporting member 31 in a manner which will be clear from the illustration in Figs. 3 and 5. When the guiding and posi-

tioning means has reached a position above the supporting member, as shown in Fig. 3, the roller 63 will be released from engagement with the cam carried by the casting 40, and the arm 74 and rod 75 will drop by gravity to their normal or inoperative position, this return movement of the clamping and holding means being cushioned by the spring 100. The guiding and positioning means, 10 however, is continued in its rotation until it reaches the position shown in Fig. 5, this mechanism having then completed its function of carrying the hemp over the upper surface of the supporting member and properly 15 positioning this hemp for feeding in a direction transverse to the length thereof. This mechanism is then released and is returned to its initial position by means of the spring 57, and during its return movement 20 the roller 63 will be engaged by the under surface of the pivoted member 84 and will swing this member about its pivot against the tension of the spring 93 until the pivoted member has passed the roller, whereupon it 25 will be returned to its normal position. As above stated in this specification, the point of release of the clamping and holding means is determined by the adjustment of the extension 68 of the flange or cam 60 carried by 30 the casting 40, and by means of this adjustable extension the hemp can be held in engagement with the supporting member 31 for a greater or less length of time. It is desirable, however, that this clamping and 35 holding means be released as soon as the guiding and positioning means has swung the free ends of the hemp to a sufficient distance to insure their being properly placed on the supporting member, since the conveyor 34 is constantly in operation, and if 40 the hemp is held for too long a period the fibers might be broken or tangled by the retarding action.

From the above description of the construction and operation of my improved hemp handling mechanism, it will be evident that an efficient and practical construction has been provided for accomplishing the objects outlined, and a construction by 45 means of which the hemp may be received from a hemp brake and may be quickly and accurately positioned in such a manner that it may be fed in a direction transverse to its length into a scutcher or any other desired 50 cleaning mechanism. The use of this construction is simple and the operator need not be particularly skilled, since it is only incumbent upon him to manipulate a single handle when the hemp has been delivered 55 from the braking mechanism. By means of this single manipulation by the operator the clamping, holding, guiding and positioning mechanism is set in operation and released, and the actuation of these parts is so timed 60 that careless operation will have no effect on

the performance of their functions if the initial movement of the mechanism is properly timed.

While I have in the above specification described one embodiment of my invention and have referred more particularly to hemp as the fiber operated upon, it will be obvious that this mechanism is adapted for use in connection with other fibers, and that various modifications and changes in the construction may be made without departing from the spirit and scope of the invention, as expressed by the following claims.

1. Means for handling fiber, including a supporting member in combination with means for receiving fiber as it is being fed longitudinally, and means for positioning said fiber transversely on said supporting member so that it may be fed in a direction transverse to its length. 85

2. Means for handling fiber, including a supporting member in combination with means for receiving said material as it is being fed longitudinally, and means for clamping one portion of said material on 90 said supporting member and guiding and positioning the remaining portion of said material in such a manner that it may be fed in a direction transverse to its length.

3. Means for handling fiber, including a supporting member in combination with means for receiving and clamping said material against said supporting member, and means for guiding and positioning the remaining portion of said material across said 100 member.

4. Means for handling fiber, including a supporting member for guiding and positioning said material across said supporting member, and means controlled by said guiding and positioning means for clamping said material against said supporting member. 105

5. Means for handling fiber, including a supporting member in combination with means for guiding and positioning fiber 110 across said supporting member, means for clamping said fiber against said supporting member and operative connections between said guiding and positioning means and said clamping means. 115

6. Means for handling fiber, comprising a supporting member and means for guiding and positioning said material across said supporting member, means for clamping said fiber against said supporting member 120 and adjustable operative connections between said guiding and positioning means and said clamping means whereby the period of operation of said clamping means may be varied.

7. Means for handling fiber, comprising a supporting member and means for guiding and positioning said material across said supporting member, a cam carried by said guiding and positioning means, means for 130

clamping said fiber against said supporting member and means carried by said clamping means and disposed in the path of the cam carried by said guiding and positioning means, whereby the said clamping means is actuated by said guiding and positioning means.

8. Means for handling fiber, including a supporting member in combination with means for guiding and positioning said material across said supporting member, means for clamping said material against said supporting member, an adjustable cam carried by said guiding and positioning means and means carried by said clamping means and disposed in the path of said cam, whereby said clamping means is actuated by said guiding and positioning means.

9. Means for handling fiber, including a stationary supporting member in combination with means for clamping said fiber against said supporting member, said clamping means comprising a clamping member, an arm, resilient connections between said arm and said clamping member and means for actuating said arm.

10. Means for handling fiber, including a supporting member in combination with means for clamping said material against said supporting member, said clamping means comprising a pivoted arm, a clamping member carried by said arm, a second pivoted arm, resilient connections between said second arm and said first-named arm, and means for actuating said second-named arm.

11. Means for handling fiber, including a supporting member in combination with means for guiding and positioning said material across said supporting member, said guiding and positioning means comprising a pivoted member, a plurality of arms secured to said pivoted member and extending outwardly therefrom at an angle with each other, and a shield secured to the outer ends of said arms.

12. Means for handling fiber, including a supporting member in combination, means for guiding and positioning said material across a supporting member, said guiding and positioning means comprising a pivoted member, a plurality of arms secured to said pivoted member and extending outwardly therefrom at an angle with each other, and an arcuate shield secured to the outer ends of said arms.

13. Means for handling fiber, including in combination, pivoted, guiding and positioning means, pivoted clamping and holding means and means carried by said guiding and positioning means for actuating said clamping and holding means as said last-named means is swung about its pivot.

14. Means for handling fiber, including a supporting member in combination with

means for receiving, guiding and positioning said material on said supporting member, and means actuated by said guiding and positioning means for clamping said fiber against said supporting member during a portion of the operative movement of said guiding and positioning means.

15. Means for handling fiber, including a supporting member in combination with a mechanism for guiding and positioning said material across said supporting member, means for clamping and holding said fiber against said supporting member and means including a pivoted cam member carried by said guiding and positioning means for actuating said clamping and holding means.

16. In combination, a supporting member, a conveyor disposed adjacent thereto, means for clamping fiber in engagement with said conveyor, means for clamping said fiber against said supporting member and means controlled by said last-named means for releasing the first-named clamping means as said second-named clamping means is actuated.

17. In combination, a supporting member, a conveyor disposed adjacent thereto, means for clamping fiber against said conveyor, means for clamping and holding said fiber against said supporting member and resilient connections between said last-named clamping means and said first-named clamping means whereby the said first-named clamping means will be moved to inoperative position upon actuation of said second-named clamping means.

18. In combination, a supporting member having a plurality of angularly disposed surfaces, means pivoted to said supporting member including a guiding member movable from one side of said supporting member across said surfaces, and downwardly on the other side of said supporting member for guiding and positioning fiber on said supporting member.

19. In combination, a supporting member, means pivoted to said supporting member and including an arcuate guiding member normally disposed in the position adjacent one side of said supporting member for receiving and positioning fiber across said supporting member.

20. Means for handling fiber, including in combination, receiving, guiding and positioning means, and means actuated by said guiding and positioning means for clamping said fiber during a portion of the operative movement of said guiding and positioning means.

21. Means for handling fiber, including in combination, guiding and positioning means, and mechanism for clamping and releasing said fiber actuated by said guiding and positioning means.

22. Means for handling fiber, including in

- combination, pivoted guiding and positioning means, and mechanism for clamping and releasing said fiber actuated by said guiding and positioning means.
- 5 23. Means for handling fiber, including in combination, pivoted guiding and positioning means, and mechanism for clamping said fiber actuated by said guiding and positioning means.
- 10 24. Means for handling fiber, including in combination, pivoted guiding and positioning means, and mechanism for clamping and releasing said fiber actuated by said guiding and positioning means.
- 15 25. Means for handling fiber, including in combination, pivoted guiding and positioning means and mechanism for clamping said

fiber actuated at a predetermined point in the pivotal movement of said guiding and positioning means.

26. Means for handling fiber, including in combination, pivoted guiding and positioning means and mechanism for clamping and releasing said fiber actuated at a predetermined point in the pivotal movement of said 25 guiding and positioning means.

27. Means for handling fiber, including in combination, pivoted guiding and positioning means and mechanism for clamping and releasing said fiber, said mechanism operable 30 at predetermined positions in the movement of said guiding and positioning means.

In testimony whereof I affix my signature.
LUD. HOLLAND-LETZ.
